UNITED STATES PATENT OFFICE.

CHARLES A. HORN, OF WOODHAVEN, NEW YORK, ASSIGNOR OF ONE-FOURTH TO
W. EVERETT RUNDLE, OF EAST ORANGE, NEW JERSEY, AND ONE-FOURTH TO
HAROLD E. LOMBARD, OF BLOOMFIELD, NEW JERSEY.

FURNACE-GRAVE.

1,261,389.

Specification of Letters Patent.

Patented Apr. 2, 1918.

Application filed June 5, 1917. Serial No. 172,863.

To all whom it may concern:

Be it known that I, CHARLES A. HORN, a subject of the German Emperor, residing at Woodhaven, in the county of Queens, city 5 and State of New York, have invented certain new and useful Improvements in Furnace-Grates, of which the following is a full, clear, and exact description.

This invention relates to furnace grates, 10 particularly grates of the automatic stoking type, and pertains especially to the elements upon which the burning fuel rests. Its chief object, briefly stated, is to provide a simple and effective grate in which the amount and 15 distribution of the air supply, upwardly through the grate to the fuel, can be conveniently and easily regulated or varied according to the nature of the fuel and other conditions of use. Another object is to provide 20 grate-top elements of simple form which can be manufactured at low cost and which can be readily assembled on their supports or carriers and can be removed and replaced with equal ease. To these and other ends 25 the invention consists in the novel features and combinations hereinafter described.

One form of the invention is illustrated in the annexed drawings, in which—

Figure 1 is a plan view of a portion of a 30 furnace grate using my improved grate-tops.

Fig. 2 is a longitudinal section, on a larger scale, showing several of the overlapping grate-tops in side elevation.

Fig. 3 is a cross section on line 3—3 of 35 Fig. 2, showing several grate-tops, with spacers of uniform width between them.

Fig. 4 is a cross section on the same plane as Fig. 3, but showing spacers of different widths between the grate-tops.

Fig. 5 is a cross section on line 5—5 of 40 Fig. 2.

Fig. 6 is a perspective view of a grate-top of the preferred form.

Fig. 7 is a perspective view of a spacer 45 adapted for use with grate-tops of the type illustrated in Fig. 6.

In the grate illustrated, the grate-tops 10 are carried by transverse parallel carrier-bars 11. These latter are of L-shaped cross section, with their horizontal webs or flanges securely bolted to brackets 12 which are pivotally mounted on transverse portable shafts 13. The brackets extend forwardly from the shafts, that is, toward the end of the

furnace at which the fuel is introduced. On 55 their forward faces the carrier-bars 11 are equipped with downwardly extending fingers 14 resting by gravity on lugs 15 on arms 16 which are pivotally mounted on the shafts 13 like the brackets 12. These arms are connected to links 17 which are themselves associated with suitable mechanism (not shown) at the front of the furnace by which they can be reciprocated, thereby rocking the arms 16 and imparting a combined vertical 60 and horizontal reciprocatory motion to the carrier-bars 11. These parts are more fully described (and are claimed) in my copending application Ser. No. 172,416. The plane of the shafts 13 and carrier-bars 11 is inclined downwardly from the front of the 65 grate to the rear, thereby giving the fuel-supporting surface of the grate a similar inclination, as will be readily understood.

The grate tops 10 are of elongated form, 70 preferably rather narrow in proportion to their length so that they will need no air-openings to protect them from the heat of the burning fuel. Each grate-top, the ends of which are rounded off as shown, is composed of a central longitudinal web 18, having the lateral flanges 19. On the underside at the front is a downwardly open flaring recess 20 to fit down upon the rounded upper edge of the carrier-bar, as clearly shown in 75 Fig. 2, the edges of the recess being preferably beveled as shown in Figs. 4 and 5. The grate-tops are arranged side by side in transverse series on the transverse carrier-bars, as shown in Fig. 1, with the rear ends of 80 the grate-tops of each series overlying and resting loosely upon the grate-tops of the series next in rear, as clearly indicated in Fig. 2.

The air for supporting the combustion of 85 the fuel on the grate passes from below upwardly between the grate-tops 10, which, as before stated, are preferably imperforate. For this purpose the grate-tops in the embodiment illustrated are spaced apart by 100 means of spacers or spacing members or devices 21 of inverted V-shape straddling the upper edges of the carrier-bars between the grate-tops. The outer, or upper, edges of the spacers are beveled to fit the corresponding beveled edges of the recesses 20 in the 105 grate-tops, as clearly indicated in Figs. 3 and 4.

From Figs. 3 and 4 it will be seen that the width and hence the area, of the air space between two adjacent grate-tops depends upon the width of the spacer used between the two, so that by using spacers of greater or less width the grate may have any desired air capacity. It will also be seen that if the spacers are all of the same width the air spaces will be all of the same area throughout the grate, but that by using spacers of different widths the air spaces may be larger or smaller in one part of the grate than another, as may be necessary or desirable according to conditions. In Fig. 4, for instance, the spacers shown are successively wider from left to right, the spacers at the extreme left being narrow enough to let the adjacent grate-tops come into actual contact with each other. Thus, by selecting spacers of the proper widths for the purpose practically any desired distribution of air supply over the grate can be obtained. In general, the use of removable spacers between the grate-tops is a highly advantageous feature, as it permits a wide range of fuels to be used on the same grate, merely by selecting spacers which will give the grate the air-capacity and air-distribution suitable for the particular fuel which is to be used.

The spacers are held in position on the carrier-bars and between the grate-tops by the overhang of the latter, as clearly shown in Figs. 3 and 4, though they are loose on the carrier-bars so as to partake of the movements of the grate-tops as the carrier-bars are rocked by the arms 16. It is also desirable to have the carrier-bars sufficiently close together for the rear ends of the grate-tops of each series to extend rearwardly beyond the spacers of the next series in rear, so that the spacers are well protected from heat.

It is to be understood that the invention is not limited to the construction herein specifically described, but can be embodied in other forms without departure from its spirit. Nor is it limited to use with an automatic or self-stoking grate, nor to the particular type of self-stoking grate herein illustrated.

I claim:

1. In a furnace grate, in combination, a

plurality of transverse carriers or supports; a plurality of transverse series of laterally shiftable grate-tops mounted on the carriers or supports, each series comprising a plurality of grate-tops arranged side by side on a carrier or support and extending longitudinally of the grate, with the rear ends of the grate-tops of each series overlying and resting upon the forward ends of the series next in rear; and removable spacing members of inverted V-shape arranged between the grate-tops of each series and straddling the same carriers or supports, to separate the grate-tops and provide spaces for admission of air from below the grate-tops to the fuel above.

2. In a furnace grate, in combination, a transverse support having an upwardly extending edge; a plurality of grate-tops arranged side by side on the support and having downwardly open recesses fitting down upon said edge whereby the grate-tops are removably mounted on the support; and spacers between the grate-tops having downwardly open recesses fitting down upon said edge of the support whereby the spacers are also removably mounted on the support, the spacers serving to separate the grate-tops and provide spaces between them for the passage of air through the grate and extending laterally into the recesses in the grate-tops whereby the spacers are held in place by the grate-tops.

3. In a furnace grate, in combination, a transverse support having an upwardly extending edge; a plurality of grate-tops of elongated form arranged side by side and having downwardly open recesses at their forward ends fitting down upon said upwardly extending edge of the support, the side edges of the said recesses being beveled; and spacers between the grate-tops to separate the same laterally, the spacers having downwardly open recesses fitting down upon the upwardly extending edge of the support and the spacers extending laterally into the grate-top recesses and being beveled to fit the beveled edges of the recesses in the grate-tops.

In testimony whereof I hereunto affix my signature.

CHARLES A. HORN.
